UNITED STATES PATENT OFFICE.

WILLIAM F. HENDRY, OF OSSINING, NEW YORK, ASSIGNOR TO MANHATTAN ELECTRICAL SUPPLY COMPANY, INC., A CORPORATION OF MASSACHUSETTS.

AEROPLANE GUIDING LIGHT.

Application filed April 28, 1927. Serial No. 187,295.

This invention relates to light beacons and relates more particularly to electric light beacon systems for guiding aeroplanes.

An object of my invention is the provision 5 of an aeroplane light beacon having a distinguishing characteristic which can readily be ascertained by means of an instrument carried by the aeroplane seeking guidance.

Another object is the provision of a novel 10 lighting unit for use with such a beacon system.

I accomplish these objects by utilizing as 15 a beacon light source one or more electric discharge tubes energized by alternating current of a given frequency whereby the light emitted from the tubes is caused to vary periodically and by providing on the aeroplane means for detecting the frequency of the light emitted by the beacon.

20 More specifically my invention consists in providing a light source which is periodically extinguished and in providing on the aeroplane means for detecting the frequency of the light fluctuations. The light source 25 preferably consists of a gas discharge tube of the type comprising a transparent or translucent envelope enclosing two electrodes and a filling of rare gas such as neon or helium, under low pressure. For best results the tube should be of the rectifying type such, for example, as a tube containing electrodes of unequal size, but may be of any well-known type. The means for detecting the frequency of the light source preferably 30 comprises the propeller of the aeroplane and a tachometer for registering the speed of the propeller.

An aviator using the system would view 35 the beacon light through the aeroplane propeller and then throttle the engine until the propeller appeared to stand stationary, at which time the propeller would be rotating at a speed in synchronism with the light frequency, or some whole multiple of that frequency. When an ordinary light tube and 40 source of energy is used the frequency of the light fluctuations can be determined but the propeller does not appear so clear cut as when a rectifying light tube is used. When 45 the latter type of tube is used, the propeller stands out much more clearly, due, probably, to the fact that the light is entirely out half of the time, rather than entirely out only a very short portion of the time. The 50 same effect is obtained by using a rectifying

tube could also be secured by using an ordinary light tube and rectifying the alternating supply current in such manner that a half wave only would be supplied to the tube.

60 I have suggested the use of gas discharge light tubes as it is well known that when such tubes are used on a circuit of varying voltage the light produced by the tube varies with the impressed voltage, even when 65 the voltage fluctuates at a very high frequency. However, any other well-known source of light having the same characteristics might be used as well.

The invention with its further objects and 70 advantages will be more fully explained by the following description taken in conjunction with the accompanying drawings.

In Fig. 1, which represents a beacon light 75 system according to my invention, reference numeral 1 indicates a neon tube light energized by an alternator 2 of a given frequency. 3 is an aeroplane having a propeller 4 through which the pilot views the neon tube beacon light 1. 5 is a tachometer which 80 registers the speed of propeller 4.

In Fig. 2, 6 is an ordinary neon light tube and 2 an alternator for energizing tube 6. The tube 6 might be one of several making 85 up the neon tube beacon light 1.

In Fig. 3 is illustrated another form of 90 light frequency detecting means. In this figure 7 is a disc having a cut-out portion 8. The disc 7 is mounted on a suitable bearing and is driven from the engine shaft 11 95 by means of a chain or other gearing.

Fig. 4 represents another form of light 100 tube which may be used for beacon 1. This tube 12 is of the same general rectifying type as is disclosed in United States Patent No. 1,628,045, except that the distance between the anode and cathode of the tube is made large so that sufficient light can be produced. Tube 12 comprises an envelope 13 containing two electrodes 14 and 15 and a filling of rare 105 gas at low pressure.

The operation of the system shown in Fig. 1 is as follows: The pilot of aeroplane 3 upon seeing a beacon light such as 1, views the light 1 through the revolving blades of propeller 4 then varies the speed of the engine driving propeller 4 until the propeller appears to stand stationary. When this illusion is secured the tachometer 5 would register the speed of the propeller 4, which 110

would be in synchronism with the fluctuations of light 1. The pilot would then read the tachometer and from the reading obtained would know the frequency of the 5 light fluctuations of beacon 1 and by knowing the frequency would be able to identify the beacon light. The beacon light 1 might be made of one or several tubes such as shown in Figs. 2 or 4, but would preferably 10 be made of one or more tubes such as shown in Fig. 4. With this type of tube the beacon would be shining only half of the time and hence the propeller 4 would appear more clear cut. The arrangement shown in Fig. 3 15 works in substantially the same manner as that shown in Fig. 1 except that instead of utilizing the propeller 4 as a synchronizing means, the aeroplane pilot would view the light through opening 10 in a plate 9, which 20 might be mounted on some part of the aeroplane in the line of vision in the pilot. With this arrangement by properly regulating the speed of the disc driving means the pilot would be enabled either entirely to occult 25 the light from beacon 1 or allow it to shine continuously through the coinciding openings 8 and 10 of disc 7 and plate 9 respectively. The speed of the engine with this arrangement would be determined by a tachometer in the same manner as shown in Fig. 30 1. The disc 7 might be driven by means other than the aeroplane engine, such as an electric motor, for example. In such a case the tachometer would, of course, be connected 35 to the disc so as to register its speed.

Such an arrangement as I have disclosed would be particularly useful where several beacon lights for various landing fields were grouped together. Each light would be operated at a different frequency known to the 40 pilot, and hence all the pilot would have to do would be to synchronize his indicator on various lights successively and thus determine the identity of the field he desired 45 to use.

The system might also be used on ships at sea and for other analogous uses.

It will be obvious to those skilled in the art that the invention is capable of a wide 50 variety of modifications and adaptations and that the present disclosure is intended merely to illustrate its nature without limiting its scope, which is defined in the appended claims.

55 What I claim is:

1. A vehicle guiding system comprising in combination, a vehicle, a light beacon, means whereby the brilliancy of said light beacon is periodically varied at a characteristic rate, 60 and stroboscopic means on the vehicle for determining the periodicity of said variation of brilliancy.

2. A vehicle guiding system comprising in combination, a vehicle, a light beacon; means 65 for varying the brilliancy of said beacon at

a characteristic frequency and stroboscopic means on the vehicle for determining said frequency.

3. A vehicle guiding system comprising in combination a vehicle, a rectifying electrical discharge light beacon, an alternating current source for energizing said beacon at a characteristic frequency and means on the vehicle for stroboscopically determining said frequency. 75

4. An aeroplane guiding system comprising a light beacon, the candle power of which varies periodically at a given frequency and means including the aeroplane propeller for determining the frequency of variation of the candle power of said light. 80

5. An aeroplane guiding system comprising in combination an aeroplane, a plurality of light beacons, means for periodically varying the candle power of each of said beacons at a different characteristic frequency and stroboscopic means on the aeroplane for determining the frequency of variation of the candle power of any one of said beacons. 85

6. An aeroplane guiding system comprising in combination an aeroplane, a light beacon, means for varying the brilliancy of said beacon at a given frequency, means on the aeroplane for stroboscopically determining the frequency of variation of said brilliancy 90 and common means for propelling the aeroplane and actuating said second mentioned means. 95

7. An aeroplane guiding system comprising a neon tube light beacon energized by an alternating current source whereby the brilliancy of said light is varied at a frequency in step with that of the alternating current and means on an aeroplane including the propeller thereof, for determining the frequency of said alternating current. 100

8. An aeroplane guiding system comprising in combination an aeroplane, a rectifying neon tube light beacon, alternating current means of characteristic frequency for energizing said neon tube, a propeller for driving the aeroplane through which the light from said beacon may be viewed, an engine for turning said propeller, means for varying the speed of the engine and means for indicating the speed of said engine, whereby the identity of said light beacon may be stroboscopically determined. 110

9. In an object identifying system, a plurality of spaced objects, lights on some of said objects, means for varying the brilliancy of each of said lights at a different characteristic frequency and means on another of said objects for stroboscopically determining said different frequencies. 120

In testimony whereof, WILLIAM F. HENDRY has signed his name to this specification this 26th day of April, 1927. 125

WILLIAM F. HENDRY.
